Primary Examiner — Eric Goodman*Assistant Examiner* — Megan M Majcher Hartnett*(74) Attorney, Agent, or Firm* — Klarquist Sparkman, LLP(57) **CLAIM**

I claim the ornamental design for a display screen with graphical user interface, as shown and described.

DESCRIPTION

The FIGURE is a front view of a display screen with graphical user interface showing the new design.

The dash-dot-dash and evenly spaced broken lines in the drawings represent portions of the display screen with graphical user interface that form no part of the claimed design.

1 Claim, 1 Drawing Sheet

Step 1: Your size   Step 2: Your Body Type   Step 3: Your choices

All questions are REQUIRED

Current Status Pregnant Postpartum

Current Hip Circumference (inches) 32.50 Inches

Pre-Pregnancy Jean Size (US) 01-08

Pre-Pregnancy Weight 90 lbs

Current Weight 80 lbs

Weeks Pregnant 36

Hip Contour

Pre-Pregnancy Jean

Pre-Pregnancy Weight

Current Weight

Weeks Pregnant (over or week 36)

Delivery Type C-Section/Uncertain Natural Birth

String Hip Sizing Chart   Help   Giraffe Measurements Conversion   Jean
